United States Patent Office

Des. 183,090
Patented June 24, 1958

183,090

WASHING MACHINE OR SIMILAR ARTICLE

Dean H. Freund, Benton Harbor, Mich., assignor to
Whirlpool Corporation, a corporation of Delaware

Application September 12, 1956, Serial No. 42,907

Term of patent 3½ years

(Cl. D49—1)

FIG. 1

FIG. 4

FIG. 5

FIG. 3

FIG. 2

Figure 1 is a view in front elevation of the washing machine or similar article embodying the design of my invention;

Figure 2 is a side elevational view of the machine of Figure 1;

Figure 3 is a rear view of the machine of Figure 1;

Figure 4 is a top plan view thereof; and

Figure 5 is a fragmentary sectional view taken along line 5—5 of Figure 1, illustrating the inwardly recessed contour of the control panel embodied in the machine showing my new design.

I claim:

The ornamental design for a washing machine, or similar article, as shown.
